R. L. DAY

BUILDING CONSTRUCTION

Filed August 16, 1922

UNITED STATES PATENT OFFICE.

ROBERT L. DAY, OF HUNTINGTON, WEST VIRGINIA.

BUILDING CONSTRUCTION.

Application filed August 16, 1922. Serial No. 582,277.

My invention has to do with the construction of buildings and while I provide a construction which possesses noteworthy advantages for garages it is to be understood that except where claims may require I do not restrict my invention to garages. Put briefly my object is to enable a satisfactory building to be constructed at a minimum of cost in that erection can be quickly accomplished and by the use of unskilled labor. My invention consists in whatever is described by or included within the scope of the appended claims.

In the annexed drawings:—

Fig. 1 is a perspective view of a garage constructed in accordance with my invention.

Fig. 2 is a detail view in perspective of a roof slab and portions of the vertical slabs separated from one another.

Fig. 3 is a detail view in perspective of a portion of the foundation and an adjacent portion of a side wall.

For the side-walls, roof and floor slabs when the building has floors, I employ units

that consist of each of a slab of dimensions that may be easily handled which are formed of plastic fire-proof material and which are moulded by suitable machinery at the point most convenient for the purpose so that the

work of erection is merely placing units in position to form the walls, roof and floors which work or at least for the most part calls for no skilled labor.

The side walls are composed each of two lines of slabs spaced apart one being the exterior and the other the interior of the wall so that an air space is provided and these slabs are of similar dimensions but preferably of different materials, the outside slabs being

of concrete and the inside of gypsum, the concrete being preferable to gypsum because of its weather resisting properties and the gypsum being preferable to the concrete for the inside walls for its insulating properties

because it makes a satisfactory finish and is lighter than concrete. The slabs are stood on end side by side upon a foundation or base of hollow blocks, 10, the outer concrete slabs 11 having at their lower ends rods, 11^a embedded therein which protrude far enough to enter a substantial distance into the holes in the foundation blocks and the gypsum slabs, 12, having similar rods, 13, which also enter the block holes so that when

grout is poured in the block holes to fill the

same the slabs and foundation blocks will be firmly tied together. At the upper ends the vertical slabs, 11, and 12, have respectively similar projecting rods, 14, and 15, which pass through holes, 16, provided in the roof slabs, 17, which roof slabs are ribbed or corrugated on their upper sides to receive a cement finish, 18, that is floated upon the roof slabs and filling the holes therein around the rods or dowel pins of the wall slabs and covering such rods effects the tying together of the roof slabs and the wall slabs. The cement cover floated over the roof slabs has its top surface given the proper pitch or slope to shed water.

The vertical sides of the wall slabs, 11, are reversely rabbeted, the rabbet being of a depth corresponding with the flange 19 produced thereby so that the sides of adjacent slabs overlap and form a joint by which the slabs mutually support one another and which is rendered sufficiently water-proof by the application of a cement or mortar to the outer portion of the joint.

It will be seen that the work of erection of a building in accordance with my invention may be very easily and inexpensively done because of the form of joint provided between adjacent wall slabs and the dowel-pin and cement filled opening connection between the side walls and foundation or base and the roof slabs.

The roof slabs may as shown in the drawings project beyond the side walls to make a neat finish or their edges may stop short of the outer face of the side walls, and a finish produced by a cornice or moulding. If desired instead of short rods at the ends of the side walls to form the dowels continuous rods extending entirely through the slabs may be employed which would form a reinforcement of the slabs.

What I claim is:—

1. A garage or the like having side walls composed of slabs placed side by side and overlapping one another at the sides, a base composed of blocks with openings, dowels embedded in the slabs and extending into the opening, a cement filling in such openings, a roof slab having openings above the tops of the side walls, dowels projecting into such openings, and a cement cover for the roof slabs filling such openings.

2. A garage or the like having side walls composed of slabs placed side by side and

overlapping one another at the sides, a base roof slabs filling such openings, the slabs composed of blocks with openings, dowels which form the side walls being continuous embedded in the slabs and extending into in one piece from base to roof slabs. ¹⁰
the openings, a cement filling in such open- In testimony whereof I hereunto affix my
5 ings, a roof slab having openings above the tops of the side walls, dowels projecting into such openings, and a cement cover for the
